UNITED STATES PATENT OFFICE.

JAMES SHAND, OF DETROIT, MICHIGAN, ASSIGNEE TO JOSEPH N. SMITH & COMPANY,
OF DETROIT, MICHIGAN, A CORPORATION OF MICHIGAN.

DATE OF.

1,091,398.

Specification of Letters Patent. Patented Mar. 24, 1914.

Application filed December 10, 1912. Serial No. 735,884.

To all whom it may concern:

Be it known that I, JAMES SHAND, a citizen of the United States of America, residing at Detroit, in the county of Wayne and State of Michigan, have invented certain new and useful Improvements in Latches, of which the following is a specification, reference being had therein to the accompanying drawings.

13. The invention relates generally to a latch mechanism of the lever type, especially designed for coach or motor car doors, and consists in the novel and simple construction of the mechanism, in the peculiar arrangement and combination of parts, and in various details of construction, as will be more fully hereinafter set forth.

In the drawings—Figure 1 is a perspective view of the latch mechanism embodying my invention; Fig. 2 is a longitudinal section through the mechanism; Fig. 3 is a perspective view of the main plate; and Fig. 4 is a perspective view of the cap plate.

In the drawings thus briefly described, A represents the latch casing, composed of a main plate or supporting member B and a cap plate C, both members being formed preferably of sheet metal. The plate B is stamped to form an angularly-disposed face plate D, centrally apertured at a to allow of the projection of the latch bolt E therethrough, and a similarly-disposed lug or ear F at the opposite edge. The latch, for simplicity of construction, is preferably round or substantially circular in cross section, formed with the usual beveled nose b, a reduced end or extension e, and a recess d, the purpose of which will be hereinafter set forth.

45. The cap plate I have shown as substantially semicircular, to conform to the shape of the latch-bolt, and is of a length to extend from the face plate to and over the lug or ear F, and is provided with lateral flanges e which rest upon the plate member B and are preferably welded thereto. The cap member is also recessed on each side, as at f, to allow of the passage therethrough of the latch operating lever.

50. G is a suitable coil spring for the latch bolt, and H is a latch-operating lever fulcrumed upon a pivot g on the casing member B.

55. In assembling the parts, the cap plate is arranged over the ear F, with its opposite

end in alignment with the latch opening a. The latch bolt is then inserted, and—with the assistance of the ear—locates the cap in its proper position upon its complementary casing section, and the parts are welded as previously set forth. The latch bolt is then removed and the spring inserted in the cap plate, which forms a housing, and abuts at its outer end against the lug F. The bolt is then positioned within the cap housing,— 65 the extension e within the spring, the latter bearing against the shoulder formed by the extension, and finally the operating lever H is inserted through the recesses in the cap housing and the bolt recess, and is fulcrumed upon its pivot pin. 70

From the foregoing description, it will be seen that the parts are of simple construction and may be easily and cheaply made; further, that the ear F performs the double 75 function of a positioning means for the cap housing in the assembly of the parts, and as an abutment for the spring. The operating lever likewise performs a double function, first, in constituting the operating device 80 for the latch bolt, and secondly serving by its engagement within the bolt recess to hold the bolt against rotation, thereby maintaining the beveled nose in the proper operative position. 85

What I claim as my invention is—

1. In a latch mechanism, the combination with a cylindrical latch bolt, of a casing provided with a housing within which said latch-bolt is arranged, said bolt being provided with a recess in one side thereof, and an operating lever fulcrumed on the casing extending through said housing and engaging the recess in the bolt, the engagement between the bolt and the lever holding the latch from rotation. 95

2. In a latch mechanism, the combination with a casing, comprising a plate member carrying a face plate, and a cap member of a latch bolt within the cap projecting through an opening in the face plate, a spring for the latch bolt housed within the cap plate, a projection upon the plate member forming a centering means for the cap plate in the assembly of the parts, said projection closing one end of the cap member and forming an abutment for the latch spring, and an operating lever for the latch. 100

3. In a latch mechanism, the combination with a casing formed of complementary 110

stamped metal plates, one carrying at one edge a face plate and at its opposite edge a centrally positioned lug or ear, and the other constituting a cap member of substantially semi-cylindrical form, said cap member having one end engaging and closed by the ear upon the complementary member, of a latch bolt housed within the cap plate and projecting through the face plate, a spring

within the cap member, abutting against the latch and ear, and an actuating lever for the latch bolt.

In testimony whereof I affix my signature in presence of two witnesses.

JAMES SHAND.
